(57) CLAIM

I claim the ornamental design for a two-panel scarf with attachable ends, as shown and described.

DESCRIPTION

FIG. 1 is a perspective view of a two-panel scarf with attachable ends, showing my new design;

FIG. 2 is a front elevational view thereof;

FIG. 3 is a rear elevational view thereof;

FIG. 4 is a top plan view thereof;

FIG. 5 is a bottom plan view thereof;

FIG. 6 is a left-side elevational view thereof; and,

FIG. 7 is a right-side elevational view thereof.
